UNITED STATES PATENT OFFICE.

ALONZO ALDRICH AND EARL E. BERRY, OF BELOIT, WISCONSIN, ASSIGNEES TO
BELOIT IRON WORKS, OF BELOIT, WISCONSIN, A CORPORATION OF WISCONSIN.

REMOVABLE-TYPE FOURDRINIER PAPER MACHINE.

Original application filed September 19, 1925, Serial No. 57,272. Divided and this application filed
May 21, 1928. Serial No. 279,354.

This invention relates to improvements in a removable table type of Fourdrinier paper making machine. The present application constitutes a division of our co-pending application, Serial No. 57,272, filed September 19th, 1925, wherein various arrangements of track members are shown for effecting the lateral removal of the Fourdrinier table. The present invention relates to an arrangement 10 of table members wherein inner and outer tracks are each pivotally mounted at one of their respective ends to the side beam of the Fourdrinier supporting structure and are adapted to be swung into a position parallel 15 to the side beams or at right angles thereto, with both the inner and outer tracks in each set in alignment with each other.

It is therefore an object of this invention to provide pivotally and permanently mounted track members upon certain of which the table normally rests and upon which the table may be laterally removed for facilitating the changing of the Fourdrinier wire.

It is a further important object of this invention to provide an improved removable table and supporting structure therefor, wherein the inner tracks may be kept in operative position during the operation of the machine to form a part of the supporting structure for said removable table in normal position.

It is also an important object of this invention to provide an improved removable table and supporting structure therefor, 35 wherein the table is supported on inside tracks positioned above the lower run of the wire, whereby the necessity of moving or swinging down the various wire rolls when the wire is changed is eliminated and where- 40 by the construction of the Fourdrinier structure is greatly simplified.

Other and further important objects of this invention will be apparent from the disclosures in the specification and the accompanying drawings.

This invention (in a preferred form) is illustrated in the drawings and hereinafter more fully described.

On the drawings:

50 Figure 1 is a fragmentary, diagrammatic side elevational view of a Fourdrinier paper making machine, showing a table and supporting structure embodying the principles of this invention;

Figure 2 is a plan view of the same with the 55 table removed to show the operation of the track members;

Figure 3 is an enlarged sectional view taken substantially on line III—III of Figure 2;

Figure 4 is an enlarged detail view showing the pivotal arrangement of the track members; and

Figure 5 is a fragmentary sectional view taken on line V—V of Figure 4.

There is shown in Figure 1 a portion of a 65 Fourdrinier paper machine of the removable table type embodying the principles of our invention. The reference numeral 1 indicates a supporting structure comprising a pair of spaced, parallel beams 2 and 3 extending longitudinally of the Fourdrinier structure and rigidly spaced apart by means of transverse beams 4 bolted thereto. Mounted on said supporting structure 1 are a plurality of transverse I-beams 5, which form a 70 sub-structure on which a table, designated as a whole by the reference numeral 6, is adapted to be supported while in operative position. Said transverse I-beams 5 are permanently and pivotally mounted to the front 75 longitudinal beam 3, as will later be explained, and thus form track members on which the table 6 is adapted to be moved when the wire is being changed. The table 4 comprises a pair of table rails 7, preferably 80 formed of channel beams, and extending parallel to the supporting beams 3 and rigidly connected by transverse beams 8. The usual table rolls 9, suction boxes 10, wire guide roll 11, tension roll 12 and inside wire roll 13 are 85 supported in the customary manner from said table structure 6.

A breast roll 14 and a lower couch roll 15 are separately supported independently of the table structure 6 with a wire 16 trained 90 around said breast roll 14 and couch roll 15 and passing over the table rolls 9 and suction boxes 10 as in standard practice. It should be noted that the rolls 13 and 12 are so positioned as to carry the lower run of the wire 100 below the level of the bottom flanges of the track members 5, thus permitting certain of said track members to remain in operative position supporting the table structure 6 during the operation of the machine. Return 105 wire rolls 17, supporting the lower run of the wire, are suitably journaled in bearings formed in the supporting beams 2 and 3.

Any suitable shaking mechanism may be associated with the breast roll or table structure or both.

The table rails 7 are supported by flanged rollers 18 adapted to rest upon the tracks 5, the rollers being operated by means of a driven shaft 19 to cause the table structure 6 to roll as a unit over the tracks 5.

Said tracks are arranged in pairs of inner 10 and outer tracks 20 and 21 respectively. The adjacent ends of each of the tracks in a pair are permanently and pivotally mounted to the front side beam 3 upon pivot posts 22 and 23 respectively. The pivot posts 22 are 15 mounted directly upon the top flange of the front side beam 3 and the pivot posts 23 are mounted upon brackets 24 bolted to the web of said side beam 3 and extending outwardly therefrom. The adjacent ends of the tracks 20 and 21 in each pair are provided with 20 swivel brackets 25 and 26, respectively, adapted to be mounted upon said pivot posts 22 and 23, respectively, to provide for the swinging of said tracks 20 and 21 into position 25 either parallel to the side beam 3 or transversely thereto.

Wearing flanges 33 and 34 are secured to the upper face of the top flanges of said tracks 20 and 21 respectively and these wearing flanges extend over the top of the pivot brackets 25 and 26 into closely abutting relation as at 36.

The outer free end of each of said outer tracks 21 is provided with a depending roller 35 27 adapted to support said outer track member 21 in its movement over the floor or supporting base 28.

The free ends of the inner tracks 20 are adapted to rest upon shoes 29 formed upon 40 the rear side beam 2 and to be locked in position by means of locking devices 30 secured to said rear beam 2 by brackets 31. The free ends of the inner tracks 20 also carry locking devices 32 for locking the table structure 45 6 in its normal position.

When it is desired to remove the table laterally, as in changing the wire, the outer tracks 21 are swung into transverse position in alignment with the inner tracks 20 and the table 6 is then rolled out over the aligned 50 tracks onto the outer tracks 21. The inner tracks 20 are unlocked and swung parallel to the side beam 3 and the new wire suspended in the form of a loop by any of the well-known methods. The inner tracks 20 are then 55 swung back and locked in place and the table 6 rolled onto said tracks and locked in normal position by means of a locking device 32. The outer tracks 21 are then swung out of the 60 way in parallel relation to said beam 3.

Due to the construction wherein the inner tracks 20 lie above the lower run of the wire in its normal position, said inner tracks may be kept in operative position during the running of the machine without interfering with 65

the wire and may therefore form a permanent part of the supporting structure for the table.

The additional labor of elevating the table structure, as required by the construction of certain types of removable Fourdriniers, is thus saved in a Fourdrinier structure of our invention. Furthermore, the fact that the table structure may be normally supported directly upon the inside tracks simplifies the construction and operation of the Fourdrinier portion of the machine. 75

We are aware that many changes may be made and numerous details of construction may be varied through a wide range without departing from the principles of this invention, and we, therefore, do not purpose limiting the patent granted hereon otherwise than necessitated by the prior art. 80

We claim as our invention:

1. In a paper making machine, a table, a 85 supporting structure therefor and a plurality of track members upon which said table may be removed comprising inner and outer pivotally mounted rails.

2. In a paper making machine, a table and 90 a supporting structure therefor including side beams and inner and outer track members pivotally mounted from said side beams.

3. In a paper making machine, a table and 95 a supporting structure therefor including side beams and inner and outer track members pivotally and permanently mounted from said side beams.

4. In a paper making machine, a table and 100 a supporting structure therefor including side beams and inner and outer track members pivotally mounted from said side beams, said track members being adapted to be swung at right angles to said side beams in aligned positions.

5. In a paper making machine, a table and 105 a supporting structure therefor including side beams and inner and outer track members pivotally mounted from said side beams, said track members being adapted to be 110 swung at right angles to said side beams in aligned positions, and means on the outer of said track members for supporting the free ends thereof when moved into said last mentioned position. 115

6. In a paper making machine, a table and 120 a supporting structure therefor including side beams and inner and outer track members pivotally mounted from said side beams, said track members being adapted to be 125 swung at right angles to said side beams in aligned positions, and rotatable means on the outer of said track members for supporting the free ends thereof when moved into said last mentioned position.

7. In a paper making machine, a table 130 structure, parallel supporting beams therefor and a plurality of track members each permanently pivoted at one end to said beams and adapted to be swung into positions par-

allel or transverse to said beams, said table into positions parallel or transverse to said structure being adapted in normal position to rest directly upon certain of said tracks. 10

8. In a paper making machine, a table structure, parallel supporting beams therefor and a plurality of inner and outer track members each permanently pivoted at one end to said beams and adapted to be swung

In testimony whereof, we have subscribed our names at Beloit, Rock County, Wisconsin.

ALONZO ALDRICH.

EARL E. BERRY.
